(57) **CLAIM**

The ornamental design for a sun shade hood, as shown and described.

DESCRIPTION

FIG. 1 is a perspective view of a sun shade hood according to the first embodiment;

FIG. 2 is a front elevation view of the sun shade hood;

FIG. 3 is a rear elevation view of the sun shade hood;

FIG. 4 is a left-side elevation view of the sun shade hood;

FIG. 5 is a right-side elevation view of the sun shade hood;

FIG. 6 is a top plan view of the sun shade hood;

FIG. 7 is a bottom plan view of the sun shade hood;

FIG. 8 is a perspective view of the sun shade hood in use;

FIG. 9 is a perspective view of the sun shade hood according to a second embodiment;

FIG. 10 is a front elevation view of the sun shade hood illustrated in FIG. 9;

FIG. 11 is a rear elevation view of the sun shade hood illustrated in FIG. 9;

FIG. 12 is a left-side elevation view of the sun shade hood illustrated in FIG. 9;

FIG. 13 is a right-side elevation view of the sun shade hood illustrated in FIG. 9;

FIG. 14 is a top plan view of the sun shade hood illustrated in FIG. 9;

FIG. 15 is a bottom plan view of the sun shade hood illustrated in FIG. 9; and,

FIG. 16 is a perspective view of the sun shade hood illustrated in FIG. 9 in use.

The broken lines of the sun shade hood depict portions of the article that form no part of the claimed design. The partial human figure outlined by broken lines in FIGS. 8 and 16 assist to illustrate the sun shade hood in a position of use and form no part of the claimed design.

1 Claim, 16 Drawing Sheets
